COILER

Leonard W. Nash, Damascus, and George A. Martin, Salem, Ohio, assignors to E. W. Bliss Company, Brooklyn N. Y., a corporation of Delaware

Application June 27, 1938, Serial No. 216,174

4 Claims. (Cl. 242—78)

Our present invention relates to the art of coiling strip material and aims to provide certain improvements therein. More particularly, it relates to the method of and apparatus for coiling hot strip metal, both ferrous and non-ferrous, although it is applicable equally well for coiling such strip and analogous material in the cold state.

Heretofore difficulty has been experienced in satisfactorily coiling hot strip metal directly upon and at its speed of delivery from the last stand of a bank of hot rolling mills: (1) because of the buckling and deforming of the strip upon starting it around the mandrels of coilers now in use with the resulting waste accruing from such deformation; (2) because of the difficulty of stripping tightly wound coils from the mandrel due to the tendency of the hot metal to strongly adhere and bind on the mandrel, and (3) because of the tendency of the strip to telescope upon being coiled.

According to our present invention the foregoing difficulties are overcome and the strip received from the mill is quickly, neatly and tightly coiled and discharged from the coiler ready for storage or presentation to the pickling baths. The invention resides in the novel construction of the various parts and the relation in which they cooperate, and these will be better understood from the detailed description which follows when considered in connection with the accompanying drawings wherein we have shown a practical embodiment of our invention, and wherein—

Figure 1 is a side elevation of a coiler embodying our invention;

Fig. 2 is a front elevation of the invention with particular respect to the coiler and coil-stripping means, certain parts being broken away to better disclose the constructional features;

Fig. 3 is an axial section through the coiler mandrel with certain parts thereof shown in elevation;

Fig. 4 is an end elevation of the coiler as viewed from the left end of Fig. 3;

Fig. 5 is a section through the coiler taken substantially along the plane of the line 5—5 of Fig. 3;

Fig. 6 is a view similar to Fig. 5 showing the coiler segments in collapsed relation;

Fig. 7 is an enlarged elevation of a detail of the invention showing the arrangement of the sprayer nozzle and the blocker rolls at the strip entering station of the coiler, certain parts being shown in section to better illustrate the construction thereof;

Fig. 8 is a top plane of the nozzle with parts broken away;

Fig. 9 is an end elevation of the nozzle as viewed from the top of Fig. 8.

Referring to the drawings, the invention is shown as primarily intended for use in connection with strip 15 received on a mill delivery table 16 from a hot rolling mill (not shown) for presentation to a coiler indicated generally by the reference character 17 at substantially the speed at which the strip is discharged from the last stand of a hot rolling mill. Preferably two coilers 17 and 17' are mounted in tandem in pits below the mill delivery table as shown in Fig. 1 so that strip can be wound as fast as it is delivered from the hot rolling mill, the tandem relation being such as to permit the strip which has been wound into a coil on one of the coilers to be discharged therefrom while a subsequent strip is being wound on the other coiler. To control the coiler upon which the strip is to be wound there is provided at the rear of a pinch roll unit 18 a controllable gate 19 which is pivoted at 20 and adapted to be moved about said pivot to either deflect the strip to move downwardly toward the coiler 17 or to permit the strip to pass over the top of the gate and proceed to the coiler 17'.

The pinch roll unit 18 is mounted at the entrance side of the coiler 17 directly in line with the mill delivery table 16 and, as is conventional, consists of a small bottom roll 21 and a larger top roll 22, both rolls being preferably motor driven and the top roll being mounted so that it can be quickly raised out of contact with the strip. Any suitable means may be provided for raising the top roll 22 and, as herein shown, said means consists of an air cylinder 23 and a lever 24 which in turn is connected to the end of a piston rod 25 and to the end of a link 26 connected to the bearing housing of the roll 22. For guiding the strip through the pinch roll unit so as to center said strip with respect to the center line of the coiler, suitable lateral guides 27, best shown in Fig. 2, are provided. These guides may be suitably adjusted in accordance with the width of the strip to be coiled by means of a motor 28, a reducing gear 29 and the attendant lever and crank connections as shown, all of which are common to the art and do not require detailed description. A second pinch roll unit 18' is disposed at the entrance side of the coiler 17' and as the unit 18' and the coiler 17' are in all respects the same as the units 18 and 17 respectively, the description will be limited to the first

mentioned units with the understanding that it will be applicable to both.

Above the coiler 17, at the entrance guideway thereto, there is mounted a pair of throat rolls 30 (Figs. 1 and 7) which, according to the present invention are preferably normally separated several inches apart and are merely employed for the purpose of facilitating guiding of the strip and helping to keep it from bearing too hard on the cast iron guides 30a and 30b.

The strip, upon passing through the throat rolls 30, is guided onto the coiler 17 to be coiled therearound. The coiler 17 comprises a collapsible mandrel 31 (Figs. 3 to 6) which, when fully expanded, has a truly cylindrical surface contour which is conducive to better and more efficient coil formation. More specifically, the mandrel 31 is of the segment and wedge type and comprises a plurality of arcuate segments 32 circumferentially disposed about a rotatable core 33, the said segments being axially spaced apart by a plurality of wedge elements 34, the segments 32 and wedges 34 being connected to the core or to a part fixedly carried by the core through the medium of links 35 and 36 respectively. The segments and wedges are mounted for simultaneous movement axially of the mandrel by being connected to one end of a shaft or rod 37 through a disk 38 mounted on said shaft, and Z-shaped connecting elements 39 mounted on said disk 38 and extending into interior circumferential recesses 40 and 41 in the segments and wedges respectively adjacent their discharge ends. As an aid in assembling the arcuate segments 32 and the wedges 34 into cylindrical form around the core 33, plates 42 are employed for connecting pairs of the Z-shaped elements together.

Upon inspection of Figs. 3 and 5 of the drawings it will be apparent that the links 35, which are connected to the arcuate segments 32, are somewhat longer than the links 36 which are connected to the wedges 34. These links are made of different lengths so that as the rod 37 is moved outwardly, that is to the left in Fig. 3, the wedges 34 will move radially inwardly more rapidly than will the segments 32, through which cooperative action it will be appreciated that the movement of the segments 32 will not be hampered or interfered with during collapsing and expanding the mandrel. The inner faces of each of the arcuate segments 32 at the lateral sides thereof, are preferably flat and lie in a common plane of the plane chord of the cylinder of which said segments form a part. It will also be noted that as herein disclosed, four segments are employed and the inner faces of these are preferably disposed at substantially right-angles to each other and when the mandrel is collapsed the inner faces of these segments form substantially a square prism as will be apparent from inspection of Fig. 6. For cooperation with the inner faces of the segments 32 the wedges 34 have their outer faces disposed at substantially right angles to each other and are so dimensioned that when they are in expanded relation to the core their outer faces will fill the gaps between the edges of the arcuate segments to provide a truly cylindrical surface.

To facilitate the assembly of the arcuate segments 32 with respect to the core 33, the links 35 of each segment are connected to a filler block 43 which is mounted within a slideway 44 in the core. To insure the driving action of the segments 32 by the core 33 during rotation thereof

in addition to the driving action provided by the links 35, which are connected to depending ears 45 on the segments and pins disposed in grooves 46 in the filler blocks 43, each filler block is formed with lugs 47 disposed longitudinally between the links 35 and extending radially between the ears 45 on the segments. Preferably the discharge end of the mandrel is curved or bevelled inwardly, as indicated at 48, to facilitate the discharge of the coil therefrom.

10 The mandrel is preferably rotated through the core, the links, and the ear and lug connections above described by having the core connected for rotation by the shaft of a driving unit 49 which is suitably driven by a variable speed motor 50. The mandrel is collapsed by the outward movement of the rod 37, the rear end of which is connected to the piston of an air cylinder 51 which is mounted at the rear of the shaft of the mandrel driving unit 49.

15 Spaced circumferentially around the surface of the mandrel 31 and normally held under pressure in rolling contact therewith are a plurality of axially extending blocker rolls 52 (Figs. 1 and 7). Preferably these rolls are mounted in pairs, each pair upon a frame or carrier 53 mounted to slide in fixed guides 54 disposed radially with respect to the mandrel. Each frame or carrier 53 is connected through a link 55, a bell crank lever 56, and a link 57 to a piston rod 58 of a piston 20 (not shown) mounted within a cylinder 59. Preferably a single cylinder and piston are employed for controlling the movement of two of the frames or carriers 53 as best shown in Fig. 1 in which case one of the bell-crank levers 56 is directly connected to a cylinder by a link 57. Suitable fluid pressure may be supplied to the cylinders 59 for controlling the movement of the pistons therein and the control of this pressure 25 may be manual by an operator at a point spaced from the coiler or in any other suitable manner. The rolls 52 may be positively driven by a motor carried by each of the frames 53, or by merely having the rolls 52 held in pressure engagement 30 with the mandrel and frictionally driven thereby. By having the blocker rolls operating in slides and arranged in pairs, each pair of rolls always maintains an equal spacing about the circumference of the coil as it builds up in diameter, 35 regardless of the diameter of the coil.

40 Directly in advance of the throat rolls 30 and the guide 30b there is a spray nozzle 60 disposed for discharging fluid under pressure (preferably water) against the surface of the strip substantially at the line of tangency of said strip with the mandrel or the surface of the convolution of a coil formed on said mandrel. The purpose of this spray is to form a film of vapor between the coil and the mandrel and between successive convolutions of the coil. The nozzle 60 is illustrated in detail in Figs. 8 and 9 and comprises a housing having a hollow chamber 61 extending longitudinally thereof and from the forward end of which spray ducts 62 extend. The nozzle housing also has a duct 63 through which fluid enters the chamber 61. The fluid 45 may be conducted to the nozzle through a suitable hose or conduit 64 and the flow of said fluid may be manually controlled by an operator, or automatically, as desired. The nozzle 60 is preferably mounted to pivot about the axis of the entering blocker roll shaft so that the nozzle will recede with the blocker roll as the coil builds up. For providing this pivotal connection, the ends of the nozzle housing are formed with lugs 65 for en-

gagement with the shaft of the blocker roll 52a, shown in Fig. 7. For further controlling the movement of the nozzle as the coil builds up, so as to maintain the tangential relation of the discharge ducts 62 of the nozzle with respect to the surface of the strip and its cooperating coil forming surface, the nozzle housing has connected thereto links 66, which in turn are connected through bell crank levers 67 mounted on the blocker roll frame 53 and links 68 to the bell 10 crank levers 56 of the blocker roll-operating unit.

In view of this mounting of the nozzle with respect to the blocker roll 52a, it will be apparent that as the coil builds up the nozzle will be constrained to move in a direction to maintain its substantially tangential relation with the surface of the coil at its point of tangency with the blocker roll 52b.

For stripping the coil from the mandrel we provide a stripper element 69 (Figs. 1 and 2) which, as herein shown, has a semi-circular or bifurcated portion 10 having an internal diameter slightly less than that of the mandrel when expanded so as to engage the innermost convolution of the coil when supported by the mandrel in collapsed condition. Depending from the forked portion 10 is a radial arm 11 the lower end of which is connected to a ram-rod 72 which is suitably guided in its movements and is operable by a piston (not shown) mounted within a fluid pressure cylinder 73.

Operation.—In the operation of coiling hot strip with the coiler hereinbefore described, two methods have been tried out successfully.

According to the first method, the rolls of the pinch roll unit 18 are together and the strip is entered therethrough down onto the mandrel over the guide 30a, throat rolls 30, guide 30b, and the top of the nozzle 60. After one or two convolutions of the strip are wound about the mandrel, which is driven at the same speed as the pinch rolls, the roll 22 of the pinch roll unit is raised and the coil is wound up with no tension except its own weight.

According to the second method, the strip is wound with a certain predetermined tension somewhat similar to winding on a cold strip mandrel. Where this is to be accomplished the rolls of the pinch roll unit 18 are held together throughout the coiling operation and by means of an electrical control fairly constant tension can be maintained between the pinch roll unit and the mandrel. For varying the speed of the mandrel as the coil builds up, there may be connected to the blocker roll 52b a lever or other equivalent means for operating a rheostat (not shown) to vary the current supplied to the motor 50.

In the operation of the coiler according to either of the methods above briefly described, the mandrel is rotated, the blocker rolls are moved into engagement with the mandrel and held in such engagement by pressure admitted to the cylinders 59. The blocker rolls may be either positively driven or frictionally driven by the rotation of the mandrel and as the leading end of the strip 15 is fed onto the mandrel which has a lineal speed approximately equal to the speed of the strip, the strip will be constrained to pass around the mandrel by the set of blocker rolls. To insure such action wedge blocks 14 may be positioned between the rolls of each pair and the end of the frames 53 may be also so shaped to promote this action. Prior to and during the strip coiling operation water under pressure is sprayed between the underside of the strip and 75

the coil forming surface for the purpose previously set forth. As the coil builds up it is driven (kept rotating) by the mandrel on the inside of the coil. This keeps the coil winding up tight. 5 As the coil builds up the pressure of the blocker rolls against the coil increases slightly but this has been found not to be detrimental. However, should it be desired to maintain a constant pressure of the blocker rolls on the coil as it builds up a blow-off or relief valve may be connected to each of the cylinders 19 to maintain a constant pressure acting on the pistons therein.

When the strip has been completely wound onto the coil, the mandrel is stopped, the pressure acting on the pistons 59 is reversed so as to withdraw the blocker rolls out of engagement with the coil. The mandrel is then collapsed by admitting fluid pressure into the cylinder 51 to move the rod 37 outwardly, which movement carries the Z-bar plates 39 with it to longitudinally move the mandrel sections and in view of the link connections between said sections and the mandrel core, the mandrel sections are caused to move radially inwardly or collapse. The stripper 69 is then operated by admitting air into the cylinder 73. Movement of the stripper will operate to discharge the coil from the mandrel onto a suitable platen 75 from which it may be transferred as desired. As the stripper moves to strip the coil it would also have the tendency to move the mandrel in the direction for collapsing in the event of its sticking and thereby insures the collapse of the mandrel independently of the movement of the plunger 37.

35 As one coil is being stripped and discharged from the coiler, a subsequent coil can be wound by controlling the gate 19 to guide the strip to the other coiler mounted in tandem with the first. In this manner the strip can be coiled and discharged from the coilers for either storage or presentation to the pickling baths as rapidly as the strip can be delivered by the hot rolling mills.

It will thus be seen that we have provided a coiler and a method of coiling strip material 45 which greatly increases the rate at which hot strip material can be wound and the quality of the coils thus formed. It will further be appreciated that the coiler is adapted for use with strip material other than hot ferrous strip and although we have shown a preferred and operative embodiment of our invention, it is to be understood that we do not wish to be limited to the specific construction and arrangement of parts described since these may be varied within 50 the range of engineering skill without departing from the spirit of the invention, as defined in the accompanying claims.

What we claim is:

1. In a high speed coiler for hot metal strip or the like, in combination, a rotatable collapsible mandrel having a substantially unbroken cylindrical surface when in expanded condition and a plurality of rolls mounted in pairs extending parallel to the axis of the mandrel and spaced circumferentially around the surface thereof and normally resiliently held under pressure in rolling contact therewith, and means for constraining the pairs of rolls to move in straight lines substantially radially outwardly as the coil builds up on the mandrel.

2. In a high speed coiler for hot metal strip or the like, in combination, a rotatable collapsible mandrel having a substantially unbroken cylindrical surface when in expanded condition and a plurality of rolls extending parallel to the axis

of the mandrel and spaced circumferentially around the surface thereof, and normally held under pressure in rolling contact therewith, and radially disposed slides for guiding the movement of the rolls outwardly in straight lines as the coil builds up on the mandrel whereby to maintain the predetermined angular spacing of the rolls about the circumference of the coil.

3. In a coiler for metal strip or the like, in combination, a rotatable collapsible mandrel having a normally unbroken cylindrical surface for supporting and winding a strip into the form of a coil, means for guiding the strip onto the mandrel, said coil winding means including a plurality of axially extending pressure rolls adapted to move radially outwardly as a coil builds up, and a nozzle for discharging fluid under pressure against the inner surface of the strip substantially at the line of tangency of said strip and its cooperating coil forming surface, said nozzle being mounted on one of the pressure roll shafts so as to move outwardly therewith and maintain its tangential discharge relation to strip being coiled as the coil builds up.

4. In a coiler for metal strip or the like, in combination, a rotatable mandrel having a normally unbroken cylindrical surface, a plurality of axially extending pressure rolls spaced apart circumferentially around the surface of the mandrel, and normally held under resilient pressure in rolling contact therewith, means for guiding the strip to the mandrel, a nozzle at the strip entering side of the mandrel for discharging fluid under pressure against the inner surface of the strip substantially at the line of tangency of said strip and its cooperating coil forming surface, said nozzle being mounted on the shaft of the pressure roll which is rearwardly of the strip entering side of the mandrel so as to move outwardly therewith and supplemental means connecting the nozzle with the pressure roll supporting means to constrain the movement of the nozzle so as to maintain its tangential discharge relation to the strip being coiled as the coil builds up.

LEONARD W. NASH.
GEORGE A. MARTIN.
